UNITED STATES PATENT OFFICE.

FRIEDRICH ALBERT RUNGE, OF SAN MARCOS, TEXAS.

AIR-PUMP.

1,183,496.

Specification of Letters Patent.

Patented May 16, 1916.

Application filed June 15, 1914. Serial No. 845,173.

To all whom it may concern:

Be it known that I, FRIEDRICH ALBERT RUNGE, a citizen of the United States, residing at San Marcos, in the county of Hays 5 and State of Texas, have invented certain new and useful Improvements in Air-Pumps, of which the following is a specification.

This invention relates to improvements in 10 air pumps and its object is to produce a simple and efficient device of this class that is cheap to manufacture.

With the foregoing and other objects in 15 view the invention consists in the combination and arrangement of parts to be hereinafter fully described in the following specification, pointed out in the claim and illustrated in the accompanying drawings which form a part of said specification and 20 in which—

Figure 1 is a side elevation of my improved pump. Fig. 2 is a front elevation. Fig. 3 is a fragmentary portion of the device, in section. Fig. 4 is a section taken on 25 line 4—4 of Fig. 3. Fig. 5 is a section taken on line 5—5 of Fig. 3. Fig. 6 is a side view of Fig. 7. Fig. 7 is a front view of Fig. 6.

Like reference characters indicate corresponding parts throughout the several 30 views.

The reference numeral 1 designates a housing in which the greater portion of the mechanism composing my invention is disposed and within the same I provide a 35 storage tank 2 in which a close fitting piston head 3 is disposed which is carried by a piston rod 4, about a portion of which a spring 5 is disposed which rests upon said piston head. To the piston rod 4 a pitman 40 6 is connected that is connected to the angular link 7, supported in bracket 8 secured to the housing, which is bifurcated at one end to engage the clutch member 9 slidably keyed to the shaft 10 journaled in the housing, and said shaft also loosely carries the 45 clutch member 11, which carries the cog wheel 12, which is formed with the annular recess 13 in which the bifurcated end of the angular bracket 14 is disposed, said bracket 50 being secured at its opposite end to the casing 1. A wheel 15 terminally carried by shaft 10 is adapted to receive power from a belt (not shown) or the shaft may be rotated by a crank if preferred. Within the casing

1 another shaft 16 is journaled in the horizontal plane of the shaft 10 and said shaft 16 is provided with a cog wheel 17 in mesh with the wheel 12, and with cranks 18, 18 that carry the pitmen 19, 19 secured to cross-heads 20, 20 slidably disposed in the casing 1, said cross-heads engaging piston rods 21, 21 of pump cylinders 22, 22, which cylinders are connected by air pipes 23, 23 with the storage tank 2 which tank is provided with the usual air hose 24.

Operation: Rotation of shaft 10 will, through cog wheels 12 and 17, rotate shaft 16 which will operate the pump cylinders 22, 22 and cause air to be pumped into the storage tank. When the storage tank has 70 been filled with air to its intended capacity the piston head therewithin will compress the spring 5, which normally exerts a pull upon the piston rod 4 to keep the clutch members in mutual engagement, against the 75 top of the storage tank thus relieving the piston rod 4 of spring pressure and permitting disengagement of the parts 9 and 11 of the clutch, and withdrawing the driving or motive power from the clutch member 11 and cog wheel 12 thus automatically stopping the operation of the pump cylinders. Air from the storage tank may be withdrawn through hose 24 to inflate pneumatic tires or for other purposes.

What is claimed is:—

A pump of the type described, including an air storage chamber, a plurality of air pumping chambers in communication with said air storage chamber, a drive shaft 90 equipped with a fixed clutch member and a slideable clutch member, said clutch members being arranged for inter-engagement, said storage cylinder or chamber having arranged therein a piston whose rod or stem is 95 equipped with a resilient member, said resilient member being positioned intermediate the piston and the piston cylinder head with the piston normally held spaced away from said cylinder head by said resilient member, 100 an angle lever having movable connection with said slideable clutch member and a loosely jointed link connection between said lever and said piston rod, said angle lever being arranged to be actuated by said resilient member to disengage said clutch member from said fixed clutch member at a 105 predetermined position of the storage cylin-

der piston, a cranked counter-shaft, pitmen and cross head connections between said cranked counter-shaft and the pistons of said pumping cylinders or chambers, and 5 intergeared connection between said drive and cranked counter-shaft.

In testimony that I claim the foregoing

as my own I have hereto affixed my signature in the presence of two subscribing witnesses.

F. ALBERT RUNGE.
